FLUID CONTROL MEANS

Eugene C. Brisbane and Earl E. Hulker, York, Pa.,
assignors to S. Morgan Smith Company, York,
Pa., a corporation of Pennsylvania

Application May 16, 1941, Serial No. 393,718

2 Claims. (Cl. 251—121)

This invention relates to fluid control means.

An object of the invention is to provide an improved fluid control means adapted to be installed in a conduit or passage in such manner that the flow of fluid in one direction through the passage is restricted a predetermined amount and the flow of fluid through the passage in the reverse direction is unrestricted.

Another object of the invention is to provide an improved fluid control means of the above type in which a cage containing a ball valve is mounted in a casing having passages formed therein in overlapped spaced relation with a connecting passage arranged in vertical alinement to the cage so that the ball valve is supported in spaced relation to the upper end of the connecting passage for controlling the flow of fluid therethrough.

The invention also comprises certain new and useful improvements in the construction, arrangement and combination of the several parts of which it is composed, as will be hereinafter more fully described and claimed.

In the accompanying drawing the single figure is a vertical longitudinal section of a fluid pressure control means embodying the present invention.

Referring to the drawing, the improved fluid control means comprises a casing 22, adapted to be connected to a fitting 23 having a port 18 formed therein.

Within the casing 22 is a chamber 24 adapted to be supplied with fluid under pressure from a suitable source of supply (not shown).

Also formed in the casing 22 is a chamber 26 which is adapted to be connected to a sewer or other free discharge (not shown).

The chamber 26 is arranged within the casing 22 in spaced relation to the pressure chamber 24, and also formed within the casing and located between the chambers 24 and 26, is a chamber 29.

Chamber 29 is connected to the pressure chamber 24 by a port 32, and also connected to the exhaust chamber 26 by a port 33.

Communication through ports 32 and 33 is controlled by valves 36 and 37, respectively. The valves 36 and 37 are adapted to be operated as a unit in any well known manner. The valve 36 has its head disposed within the chamber 24, said valve being adapted to engage a seat 41. The valve 37 has its head disposed within the chamber 26, said valve being adapted to engage a seat 42. The valves 36 and 37 are so arranged that when the valve 36 is seated the valve 37 is unseated, and vice versa.

The chamber 29 is connected to the port 18, by a passage comprising three sections, indicated on the drawing by the reference numerals 56, 57 and 58.

5 The section 57 of the passage is contracted somewhat. That is to say, the area of the sections 56 and 58 of the passage is greater than the area of the section 57, the latter providing a reduced portion in the passage between the sections 56 and 58.

The passage 57 at the point where said passage is connected to the passage 56 may be formed with a tapered wall 59.

In the form of the invention herein shown and described, the passages 56 and 58 are arranged substantially in parallel horizontal planes, with the passage 58 disposed in a plane slightly lower than the plane of the passage 56. The end of the passage 56 farthest from the chamber 29 overlies the end of the passage 58 farthest from the port 18, and the passage 57 is vertically disposed and connects the overlapped ends of the passages 56 and 58.

In axial alinement with the vertical passage 57, the casing 22 is formed with a threaded opening 60.

Mounted in the opening 60 and supported by the threaded portion thereof, is a cage 61 comprising a cylindrical member open at the top and open at the bottom. The upper portion of the cage 61 is formed with external screw threads for engagement with the threads of the opening 60.

The lower portion of the cage 61 is formed with depending arms 62, the inner cylindrical portions of which arms are curved inwardly, as indicated at 63, to provide means for supporting a ball valve member 64.

The construction of the cage 61 is such that the ball 64 is free to move axially upwardly and downwardly within the cage. The downward movement of the ball is limited when the ball rests against the portion 63 of the arms 62.

The upper portion of the cage 61 is adapted to receive a suitable tool, such as a spanner wrench, in order to turn said cage to the desired position within the casing 22.

In order to lock the cage 61 in adjusted position, a lock nut 65 is mounted on the upper threaded portion of the cage, said nut being adapted to be turned down tight against the upper surface of the casing 22 when the cage 61 is disposed in the desired position.

Also threaded on top of the cage 61 is a cap nut 66 having on its interior a depending lug 67

adapted to provide means for limiting the upward movement of the ball 64. The cap nut 66 provides means for closing the upper portion of the cage 61. If for any reason the ball 64 should require inspection or cleaning, the cap nut 66 can be unscrewed without affecting the setting of the cage 61, thereby exposing the ball for ready inspection or replacement.

When the device is inactive ball valve member 64 will be in the lowermost position, which position of said ball is such that the ball is spaced slightly from the seat or tapered wall 59.

Since the valve 37 is unseated, port 18 is connected to the sewer or free discharge, through passages 58, 57, past the unseated ball 64, passage 56, chamber 29, port 33 and chamber 26.

When the valves 36, 37 are moved upwardly, valve 37 is seated and valve 36 is unseated. When the valve 37 is thus seated and the valve 36 is unseated, the pressure supply chamber 24 is connected to port 18, through port 32, past unseated valve 36, chamber 29, and passages 56, 57 and 58.

Due to the manner in which the ball valve member 64 is arranged in passage 56, when the fluid under pressure is supplied to port 18 from chamber 29, in the manner above described, the downward pressure of the fluid passing from passage 56, through passage 57 to passage 58, will retain the ball valve member 64 in the bottom of the cage 61. Therefore, since the ball 64 is retained by the cage 61 in slightly spaced relation to the tapered wall or seat 59, the fluid under pressure supplied to port 18 is restricted in its flow from passage 56 to passage 58 to the area of the opening between the ball 64 and the tapered wall 59. In this way the amount of fluid under pressure which is delivered to port 18 is limited to the amount of fluid that can pass through the restricted opening provided between the ball 64 and the tapered wall 59.

On the other hand, when the valves 36, 37 are operated so as to seat valve 36 and unseat valve 37, so that fluid is exhausted from the port 18, the flow of fluid upwardly through the passage 57, from passage 58 towards passage 56, forces the ball 64 upwardly away from the tapered wall 59. With the ball 64 thus moved to a position away from the upper end of the passage 57, fluid can flow unrestrictedly through the passages 57 and 56 towards the sewer or free discharge chamber 26.

Having thus described our invention, what we claim is:

1. Fluid control means comprising a casing formed with a passage, a valve seat formed in the passage, a threaded bore formed in the casing and arranged in axial alinement with said valve seat, a cage open at both ends and having a portion formed with external screw threads for threaded engagement with the threads of said bore, the threaded portion of said cage projecting above the upper surface of said casing, said cage

having a plurality of depending arms extending downwardly in said bore towards said valve seat, the lower ends of said arms having inwardly extending portions adapted to be disposed in spaced relation above said valve seat, a ball valve member mounted within said cage and adapted to be supported by the lower inwardly extending portions of said arms in spaced relation with respect to said valve seat, said ball being freely movable within said cage, a lock nut mounted on the upper threaded exteriorly disposed portion of said cage and adapted to be turned down tightly against the upper surface of said casing to retain the cage in adjusted position within said bore, and a cap nut threadedly mounted on the upper portion of said cage above the lock nut, said cap nut constituting means for closing the upper open end of said cage and being adapted to be unscrewed from said cage to expose the ball for inspection or replacement without affecting the position of the cage within the bore of the casing.

2. A valve of the class described, comprising a casing having two passages formed therein, one said passage extending from an end of the casing inwardly to a point interiorly of the casing, the other said passage extending from the other end of the casing inwardly to a point interiorly of the casing, the inner end portions of both passages being arranged in overlapped spaced relation with respect to each other, a connecting passage extending from the inner portion of one said passage to the inner portion of the other said passage, a valve seat formed in said connecting passage, a threaded bore formed in the casing and arranged in axial alinement with said valve seat, a cage open at both ends and having a portion formed with external screw threads for threaded engagement with the threads of said bore, the threaded portion of said cage projecting above the upper surface of said casing, said cage having a plurality of depending arms extending downwardly in said bore towards said valve seat, the lower ends of said arms having inwardly extending portions adapted to be disposed in spaced relation above said valve seat, a ball mounted within said cage and adapted to be supported by the lower portions of said arms in spaced relation to said valve seat, said ball being freely movable within said cage, a lock nut mounted on the exteriorly disposed portion of said cage and adapted to be engaged tightly with the upper surface of said casing to retain the cage in adjusted position therein, and a cap threadedly mounted on the upper portion of said cage above said lock nut, said cap closing the upper open end of said cage and being removable from said cage to expose the ball for inspection or replacement without affecting the position of said cage within the casing.
